PIPE CARRIER

Samuel P. Hull, Yonkers, and John J. Corcoran, Albany, N. Y., assignors to Railroad Accessories Corporation, New York, N. Y., a corporation of New York

Application October 16, 1936, Serial No. 105,854

11 Claims. (Cl. 308—7)

This invention relates to fixtures for supporting pipes, rods and like members in such a manner as to permit free lengthwise movements of the members, as in systems for the actuation of railroad switches and signals; especially to so-called "transverse pipe-carriers", by which such operating members are supported at regions where they extend under the tracks; and more particularly to such carriers having supporting elements lagged to the ties of a railroad comprising several tracks.

Conventional forms of transverse pipe carriers, when used at mechanical interlockings for the support of pipe lines mechanically operating switches and signals, where such pipe lines cross under the tracks, from parallel lines of such pipes to the unit controlled, are supported on the ties and provided with rollers, but are generally non-adjustable. Track elevation, however, varies with respect to that of adjacent parallel tracks, and is changed frequently by the raising of the tracks, or to provide for different elevation of adjacent rails required by the curvature of the tracks.

Under such conditions, the use of non-adjustable roller carriers is far from satisfactory, as it is often necessary to provide for adjustments of one pipe entirely independently of any other pipe in the series, and this can not be accomplished by any ready manipulation of the conventional pipe hangers, and in some cases a change of intrinsic unimportance involves a readjustment attended by inordinate disturbance of the associated structures. This can easily introduce an element of actual danger into this very essential and sensitive part of the operating organization of a railroad system.

It is, therefore, the general object of the present invention to provide a novel form of pipe-hanger with a plurality of roller carriers each adapted to support in free-running fashion a lengthwise movable operator pipe, rod or like member, in such a system; and to provide an attachment means for each of said carriers by which the carriers severally can be secured in various adjusted positions relatively to each other upon an upright part of said hanger, independently of each other, and each being removable from the hanger without disturbing the attachment of another carrier.

Another object of the invention is to provide for free-running of the pipe lines at all times by a novel organization of roller supports so mounted adjustably upon the ties as to allow installation and adjustment to the proper elevation with-

out cutting into the ties and without shimming up the pipe carriers. A cognate object is to provide means by which, when track elevation is changed after installation, the vertical position of the pipe line relatively to the bridging bracket or member lagged to the ties across the gap between ties, may be adjusted, without cutting ties, to compensate for changed elevation of track, and consequently to eliminate friction between the pipe line and its roller-carriers.

Still another object is to provide such mounting means as will permit the installation of the carrier and its support on adjacent ties regardless of ordinary variation in width of the inter-tie spaces usually encountered in making such installations, thus avoiding the need for re-spacing the ties; also to permit horizontal alignment after installment, made necessary frequently by the shifting of the ties in use.

Among other objects is to provide for supporting the rollers, where there is more than one run of pipe, with staggered centers upon their respective carriers, so that the rollers and their journal pins can be removed readily, and without loosening the carrier from the tie, as is necessary with the present standard fixed transverse pipe carriers when two pipe lines are supported side by side. Ordinarily, when two lines are so supported, they are at the same level but occasionally one of these pipes, due to the fixed elevation of its end, has to be slightly above or below the adjacent pipe, and it is a further object of the present invention to provide for this adjustment.

Other objects and advantages will appear as the description of the particular physical embodiment selected to illustrate the invention progresses, and the novel features will be particularly pointed out in the appended claims.

In describing the invention in detail and the particular physical embodiment selected to illustrate the invention, reference will be had to the accompanying drawings and the several views thereon, in which like characters of reference designate like parts throughout the several views, and in which:

Figure 1 is a view in vertical sectional elevation of a transverse pipe carrier forming part of a mechanical switch and signal system, and in which the present invention has been embodied; Fig. 2 is a plan view of the parts as shown in Fig. 1, mounted upon adjacent ties of a railroad track; Fig. 3 is a fragmentary detail view in vertical section, and upon a larger scale, taken on the line III—III of Fig. 1, the arrows at the end of the line indicating the direction in which the

view is taken; Fig. 4 is a similar fragmentary detail view taken on the line IV—IV of Fig. 1; Fig. 5 is a view in front elevation of a pipe hanger of modified construction, taken separately from the track structure, and on a larger scale than that shown in Fig. 1, the end portions of the bridging bracket being broken away, to save space in the drawings; Fig. 6 is a view in side elevation of the pipe hanger shown in Fig. 5; Fig. 7 is a fragmentary detail view in vertical section, taken on the line VII—VII of Fig. 5; Fig. 8 is a fragmentary detail view in horizontal section on the line VIII—VIII of Fig. 5; Fig. 9 is a view in front elevation of another modification of the pipe hanger embodying our invention; Fig. 10 is a fragmentary detail view in vertical section on the line X—X of Fig. 9; Fig. 11 is a view in vertical section on the irregular line XI—XI of Fig. 9; and Fig. 12 is a detail view in elevation of the roller-carrier member shown at the left-hand side of Fig. 9, without its roller, and separately from the supporting structure.

In one particular physical embodiment of the invention selected for illustration and description, the parts designated respectively by the reference characters 11 and 12 are railroad ties, laid in parallel, adjacent relation, spaced apart with a gap of desired width therebetween, the track rails being omitted, as unnecessary for a proper understanding of the invention. Upon these ties is lagged, as by lag-screws 13, a bridging bracket or member 14, which may be made of any suitable material, length and cross-section to serve the intended purpose of the invention. It is shown as having V-shaped ribs 15 extending below each end to prevent shifting thereof when lagged to the ties.

A slot 16 is provided at each end region, as shown in Fig. 2, transfixed by one of the lag screws, to permit the bridge to be shifted lengthwise for adjustment prior to driving the lag screws home. The structure of the bridge at this medial region includes plate-like portions 17 and 18, disposed horizontally, so as to lie flat upon the ties, and to afford lateral rigidity; and it includes an upright standard, post or part, 19, formed in the instance illustrated as a web, integral with the bridge.

From the web 19 depends a series of hanger uprights 20, 21 and 22, referring more particularly to Figs. 1 to 4 inclusive, each serrated horizontally as at 23, and each having a longitudinal slot 24, terminated by a small web 25 at the ends respectively. Stiffening arches 26 act to brace the hangers, and also to constitute this portion of the bridge a sturdy support for the rollers 27, on which the pipe lines 29 and 30 are carried, in pursuance of the invention.

The rollers are disposed in staggered positions, relatively to the length of the pipe lines, and each roller is provided with its own yoke-shaped carrier member, as at 31 and 32. Each yoke has two arms, 33, and each arm has an orifice 34 (see Fig. 3) in which is journalled a pin 35, acting as a shaft for one of the rollers, the latter having grooved peripheries 36, conforming more or less closely to the contour of the pipes or rods carried thereby. Cotter pins 37 act to retain the pins 35 in place, and may be readily removed to permit withdrawal of one or more of the rollers and/or of the pipes, without disturbing the carrier yokes or any other part of the structure.

At 38 each of the yoke members is formed with a planiform web, sufficiently wide to overlap at each side the ribbed portions 23 of two of the

series of slotted hangers. The web 38 of yoke 31 overlies the hangers 20 and 21, and is secured adjustably in vertical relation thereto by bolts 39 transfixing elongated slots 40a in the web 38. The yoke 32 is disposed at the other side of the bridge 19, and its web 38 is bolted thereto, as at 39. The pin 35 of yoke 32 (see Fig. 2) can be easily withdrawn and inserted, as occasion requires, without interference with a similar withdrawal and insertion selectively of the pin 35 of yoke 31.

The webs 38 of each yoke have at their bolt holes 40 a ribbed or serrated inner face which is adapted to act in complement of the serrated faces 23 of the respective hangers, as illustrated clearly in Fig. 4. By this means the carrier roller 15 for each pipe can be secured rigidly in any selected position throughout a wide vertical range of such positions, and differences of level encountered either at the time of installation, or at any time, in use, may be readily and rapidly compensated for, to bring the pipes to the same level, or either of them to any desired level.

The yoke members 31 and 32 are shown as provided with web-like reinforcements 44, the contour of which can of course be varied as desired and found suitable.

In a now-preferred embodiment of the invention, as illustrated in Figs. 5 to 8 inclusive, the feature of entire independence between the roller carriers, and therefore between the pipe lines, has been developed to an optimum extent, and in this embodiment of the invention, the bridge 4 is intended to be disposed upon adjacent ties, just as in the structure shown at 14 in Fig. 1, it being understood that the feet of the bridge 4 are broken away merely to save space in the drawings.

The web 9 in this form of the invention has fewer rows of serrated ridges, only four being shown at each side, as at 23x, but these serrated ridges are so disposed that the clamping members 40 5 and 6 of the yokes R' and R'' respectively are severally of only sufficient width to span each a pair of the serrated ridges 23x, and so do not interfere with each other in any adjustive position to which either of the yokes may be moved vertically.

It will be observed that it is thus easy to mount both of the yokes on the same side of the web 9, if the limitations of space should so require, inasmuch as when the yokes are at the levels occupied by them respectively in Fig. 5, either of the journal pins 34 may be withdrawn without interference by the other yoke with such withdrawal. It will be noted further that by this arrangement of the serrated ridges 23x on each side of the 55 gaps 2, it has been made possible for the bolts B of the clamps to traverse the gaps, and as a consequence we have provided in this form of the device for withdrawal of each of the clamps bodily down through the open end of the appropriate gap 2, without disassembling the clamp or removing it from the pipe.

In a modified form of the invention as shown in Figs. 9 to 12 inclusive, the bridge member 54, of which the middle portion only is shown, is to be considered as corresponding in essential respects with the similar part of the structure illustrated in Figs. 1 and 2, and described with reference to those figures, so that it is not necessary to repeat said description of its structure and mode of installation upon the ties.

This modification has been designed to afford a somewhat lighter form of structure, and also presents certain desirable qualities of compactness, simplicity of manufacture and economy in 75

cost. It differs from the earlier described forms of the hanger in that it has only a single upright 55, the cross-section of which, as shown in Fig. 11, is substantially H-shaped, having at its four corners longitudinal ribs 56 and 57, of which two are substantially rectangular in cross-section as 56, and are provided with serrations, as at 53, while the other two, as 57, are rounded at their salient portion.

10 The carrier yokes for this type of hanger are all formed like that illustrated in Fig. 12, comprising a body or web 58 in the shape of a slab, pierced as at 59, to pass a hook-bolt 60, of which the hook portion is engaged, as shown in Fig. 11, 15 with one of the rounded ribs 57, the other end of the shank, as at 62, being threaded and fitted with a retaining nut 63, and a lock-washer 64.

The body 58 has a shoulder 66 extending along one edge thereof adapted to extend over the serrated edge 56, and along this shoulder is formed 20 a series of teeth 65, adapted to be engaged tentatively with the serrated portion 56 of the upright 55. At the other side of the serrated ridge 56 a grooved buttress 67 is formed, one side 25 of which lies against the face 52 of the upright, while the shank 61 of the hook-bolt fits into the groove 68, the parts thus fitted together constituting a very sturdy fitment, as will be readily understood by those skilled in the art.

30 The entire fitment can be slipped on and off the upright 55 over its free end 50, without the need for any disassembly of the hook-bolt from the clamp body, and thus there is less danger of any of the parts being lost. The roller R, in this 35 form of the device, is journaled on a pin 34 secured in the yoke ends 51 by cotter pins 37, as already described with reference to the other structures.

From the foregoing disclosure, it will be readily apparent that in each of the forms illustrated, the several structures shown provide fully for the accomplishment of the several objects set forth in the opening statement of the invention.

For example, whichever of the forms be used, 45 if either tie, as 11, for example, be moved in either direction, i. e., toward the right or toward the left from the position shown, it is only necessary to loosen the appropriate lag screw 13, or if necessary, both of them, without disturbing the 50 correct alignment of the pipes 29 and 30, in the system, and the re-adjustment to the new position of the tie can be effected. Either, or both, of the ties can be raised or lowered at will, and compensatory adjustment of one or both of the 55 yokes 31 and 32 can be effected by simply loosening either or both of the bolts 39, and shifting the yokes to correct position upon their hangers 20 and 21, or 21 and 22, as the case may be, having reference to the form of the device shown 60 in Figs. 1 to 4, inclusive. Then the bolts 39 will be tightened, no other change in the positions of the parts being ordinarily necessary. Keepers 41, each with one serrated face to be engaged with serrations on the bridge web surfaces, may 65 desirably be provided, and lock-washers 42, interposed between the keepers and the nuts 43, in usual fashion. Small lugs 40 may be provided to hold the bolt heads or nuts against rotation.

70 The operation of the form of the device illustrated in Figs. 5 to 9 inclusive, and of the modification shown in Figs. 10 to 12 inclusive has been indicated with sufficient clarity in the 75 course of the description of those forms, so that

further description thereof will not now be necessary.

It is to be noted particularly that all necessary compensatory adjustments may be accomplished without cutting into the ties, or either of them, 5 and without the need for using shims, wedges or any other loose form of level-adapter.

Although we have particularly described several particular physical embodiments of our invention, and explained the operation, construction and principle thereof, nevertheless we desire to have it understood that the forms selected are merely illustrative, and do not exhaust the possible physical embodiments of the idea of means underlying our invention. 10 15

What we claim as new and desire to secure by Letters Patent of the United States, is:

1. A pipe-hanger of the class described: comprising a bracket member adapted to be secured to the upper face of a support, such as a railroad tie, and having an integral upright carrier-support, a plurality of roller carriers each adapted to support a lengthwise movable device, such as an operator pipe or rod in a switch and/or signal actuating system; and an attachment means for each of said carriers by which the carriers severally can be secured in various adjusted positions relatively to each other upon said upright carrier-support, to dispose the carriers in selected vertical positions independently 30 of one another, said upright carrier-support being constructed and arranged to extend rigidly into the space beside the tie and below the level of a rail, with said attachment means and the roller-carriers. 35

2. A pipe-hanger of the class described: comprising a bracket member adapted to be secured to the upper face of a support, such as a railroad tie, and having an integral upright carrier-support, a plurality of roller carriers each adapted to support a lengthwise movable device, such as an operator pipe or rod in a switch and/or signal actuating system; and an attachment means for each of said carriers by which the carriers severally can be secured in various adjusted positions relatively to each other upon said upright carrier-support, to dispose the carriers in selected vertical positions independently 40 of one another and each being removable from said support without disturbing the attachment 45 of another carrier, said upright carrier-support being constructed and arranged to extend rigidly into the space beside the tie and below the level of a rail, with said attachment means and the roller-carriers. 50

3. A pipe-hanger device of the class described: said device comprising a bracket adapted to be secured at each end to spaced supports, such as adjacent railroad ties, bridging the space therebetween; said bracket being provided intermediate its ends with at least one roller carrier adapted to support below the rail level a lengthwise movable member, such as an operator pipe or rod in a switch and/or signal actuating system; said device being characterized by means 60 to permit adjustment of said bridge ends slidingly upon said support; and means to permit adjustment of each roller carrier in the space between the ties, and below said rail level, to a selected fixed position with respect to said 65 bridging bracket. 70

4. A pipe-hanger device as claimed in claim 3, in which a plurality of said roller carriers are supported from said bridging bracket with removable means by which each roller carrier can 75

be attached to said bridging bracket, adjusted vertically thereon, and removed therefrom, without interference with any other roller carrier, said bridging bracket being provided with means 5 to permit its movement bodily with said roller carriers to shift the roller-carriers in the space between the ties laterally with respect to said ties, said bracket having sharp ribs on its lower face adapted to bite into the upper surface of 10 the ties, when fitted thereto.

5. A pipe-hanger device as claimed in claim 3, in which a plurality of said roller carriers are supported from said bridging bracket in staggered positions with removable means by which 15 each roller carrier can be attached to said bridging bracket, adjusted vertically thereon, and removed therefrom, without interference with any other roller carrier, said bridging bracket being provided with means to permit its movement bodily with said roller carriers to shift the roller-carriers in the space between the ties laterally with respect to said ties, said bracket having sharp ribs on its lower face adapted to bite into the upper surface of the ties, when fitted 20 thereto; and lag screws adapted to transfix said ribbed bracket parts and enter the material of 25 said ties, forcing said sharp ribs thereinto.

6. A pipe-hanger device comprising the bracket with carrier-supporting upright, and a roller carrier, combined and cooperating as claimed 30 in claim 3 in which said roller carrier is constituted by a yoke member with a roller journaled in its arms, said yoke member having a serrated inner face adapted to be engaged with 35 an upright serrated face upon said carrier-supporting upright; and means to clamp said yoke to said upright in any selected position of vertical adjustment.

7. A pipe-hanger device comprising the bracket with carrier-supporting upright, and the roller carrier elements combined and cooperating as 40 claimed in claim 1, in which each roller carrier is constituted by a yoke member with a roller journaled in its arms, said yoke member having a serrated inner face adapted to be engaged with 45 an upright serrated face upon said carrier-supporting upright; and means to clamp said yoke to said upright in any selected position of vertical adjustment.

50 8. A pipe-hanger device of the class described: said device comprising a bracket adapted to be secured at each end to spaced supports, such as adjacent railroad ties bridging the space therebetween said bracket being provided intermediate its ends with a plurality of roller carriers each adapted to support a lengthwise movable member, such as an operator pipe or rod in a switch and/or signal actuating system; said device being characterized by means to permit adjustment of said bridge ends relatively to said support; and means to permit vertical adjustment 55 of each roller carrier to a selected fixed position with respect to said bridging bracket, said adjusting means for the bracket being con-

structed and arranged to permit universal adjustment of the bracket bodily in its own plane, and corresponding bodily adjustment of the roller carriers in the space between said supports, whereby the rollers in said carriers may 5 be raised, lowered, shifted laterally and turned angularly, substantially as described.

9. A pipe-hanger device comprising a bridge member having ends adapted to be secured adjustably to a supporting structure, and having an upright medial web having on each face a serrated portion with extensions serrated upon 10 at least two opposite sides to form hangers, said hangers being adapted to depend within a confined space below said bridge member, and a 15 plurality of yoke members one having a serrated face to be engaged retentively with one serrated face of said medial bridge region, and another of said yoke members having a serrated face to be engaged with an opposite serrated face 20 of said bridge, each of said yokes being provided with a removable pipe-carrying roller; and fastening devices for said yokes by which each may be secured to a serrated face of said bridge adjustably in a vertical direction, independently of 25 another.

10. A bridge member for a pipe-hanger of the class adapted to bridge the space between adjacent ties on a railroad track, said bridge comprising plate-like ends adapted to lie flat, each upon one of said ties, and having lengthwise slots to receive lag bolts or screws by which to secure said bridge adjustably lengthwise upon 30 said ties; and an upright medial web intermediate said end plates and adapted to span a space 35 between said ties, said upright web having a series of hangers depending therefrom into position to enter said space; each of said hangers having an upright slot with serrated margins, whereby said web is adapted to receive at one side a yoke member overlapping two adjacent 40 hangers, and is adapted to receive at its other side a yoke member overlapping two adjacent hangers in staggered position; and means to secure said yoke members in vertically adjusted 45 positions.

11. A carrier member for a pipe-hanger of the class adapted to serve as a transverse pipe carrier in a mechanical switch and/or signal operating system of a railway, said carrier member comprising a yoke-shaped body portion having a planiform web with bolt-receiving orifices spaced apart and having their margins serrated at the rear face of said web, the arms of said yoke being transfixed by a pin adapted to serve as a shaft or journal for a carrier-roller mounted rotatably between said arms, said carrier member being adapted for assembly with a bridge member to be supported upon adjacent ties of 50 said railroad track, spanning the space between 55 the ties.

SAMUEL P. HULL.
JOHN J. CORCORAN.
